COMBINED SOCKET HANDLE AND LAMP GUARD

Shinjiro Mori and Takezo Takamatsu, Tokyo, Japan,
assignors to Mori Denki Manufacturing Co., Ltd.,
Tokyo, Japan

Filed Aug. 10, 1970, Ser. No. 24,398

Term of patent 14 years

Int. Cl. D26—02

U.S. Cl. D48—24

FIG. 1

FIG. 2

FIG. 3

FIG. 5

FIG. 4

*FIG. 6**FIG. 7*FIG. 1 is a front elevational view of a combined socket handle and lamp guard showing the new design;

FIG. 2 is a side elevational view thereof, the opposite side being a mirror image of the side shown;

FIG. 3 is a top plan view thereof;

FIG. 4 is a bottom plan view thereof;

FIG. 5 is a rear elevational view thereof;

FIG. 6 is a longitudinal sectional view thereof; and

FIG. 7 is a perspective view thereof.

The lamp bulb is shown in broken lines in FIGS. 6 and 7 for illustrative purposes only.

We claim:

The ornamental design for a combined socket handle and lamp guard, as shown and described.
